Primary Examiner — Karen S Acker*Assistant Examiner* — Wendy Arminio(74) *Attorney, Agent, or Firm* — Brinks Gilson & Lione(57) **CLAIM**

The ornamental design for a capsule for making beverages, as shown and described.

DESCRIPTION

FIG. 1 is a bottom perspective view of a capsule for making beverages of the present invention;

FIG. 2 is a side elevation view thereof, with all other side views looking the same; and,

FIG. 3 is a bottom plan view thereof.

The top is not shown, as it forms no part of the claimed design.
